187,506

BUTTONHOLE ATTACHMENT FOR A SEWING MACHINE OR SIMILAR ARTICLE

Malcolm S. Park, Verplanck, N.Y., assignor to The Singer
Manufacturing Company, Elizabeth, N.J., a corpora-
tion of New Jersey

Application April 3, 1959, Serial No. 55,338

Term of patent 14 years

(Cl. D70—2)

Fig. 6.

Fig. 7.

Fig. 1 is a top plan view of a buttonhole attachment for sewing machines embodying my new design;

Fig. 2 is a right side elevational view;

Fig. 3 is a left side elevational view;

Fig. 4 is a front elevational view;

Fig. 5 is a rear elevational view;

Fig. 6 is a front perspective view; and

Fig. 7 is a rear perspective view.

I claim:

The ornamental design for a buttonhole attachment for a sewing machine, or similar article, substantially as shown.
